UNITED STATES PATENT OFFICE.

OLIVER C. REDDING, OF CHICAGO, ILLINOIS, ASSIGNOR OF ONE-HALF TO
WILLIAM K. KENLY, OF CHICAGO, ILLINOIS.

GYRATORY CRUSHER.

No. 850,491.

Specification of Letters Patent.

Patented April 16, 1907.

Application filed March 25, 1905. Serial No. 252,030.

To all whom it may concern:

Be it known that I, OLIVER C. REDDING, a citizen of the United States, residing at Chicago, in the county of Cook and State of Illinois, have invented certain new and useful Improvements in Gyratory Crushers, of which the following is a specification.

This invention relates to improvements in gyratory crushers, and refers more specifically to an improved crusher wherein the hopper is gyrated, while the crusher-head is devoid of gyratory movement.

Among the salient objects of the present invention are to provide a construction which enables the rock or other material to be crushed to be more readily fed into the jaws of the machine, this result being accomplished by omitting the spider-head heretofore found indispensable and bodily oscillating in a gyratory manner the hopper; to provide a construction in which the material to be delivered from the crushing-jaws is free to fall directly through the machine instead of being delivered to an inclined diaphragm, thereby avoiding the clogging frequently present in machines of the construction heretofore in use; to provide a construction which dispenses with the eccentric and eccentric-gear mechanism whereby the main shaft was gyrated, and substitute therefor a simple, easily-controllable and readily-accessible mechanism for gyrating the hopper; to provide a construction wherein all rapidly-rotating parts are dispensed with and the movement of parts which have bearing with each other are reduced to a minimum and made capable of indefinite wear; to provide a construction in which the gyrating member (the hopper) is supported upon a series of oscillating studs or struts, which permit perfect freedom of movement of the hopper in the required manner and at the same time reduce frictional resistance to a minimum; to provide a construction which enables hydraulic pressure to be utilized for gyrating the hopper in an extremely simple and reliable manner and under very perfect control; to provide a construction which is composed of relatively few parts and these of simple, practical, and strong construction, thereby reducing the cost of construction to a minimum; to provide, in conjunction with the hydraulic-pressure mechanism, certain relief or safety

mechanism, which prevents overtaxing the strength of the crusher mechanism and breaking or displacing the latter; to provide a construction the parts of which are so combined and arranged as to occupy a minimum amount of floor-space, and nevertheless afford ready access to all working parts; to provide means for readily adjusting the crusher to vary the size of the product and other means for varying the relative movement of the crusher members, so that the rate at which the material is fed through the machine may be commensurate with the degree of fineness to which it is reduced, and in general to provide a simple and improved construction of the character referred to.

The invention consists in the matters hereinafter described, and more particularly pointed out in the appended claims.

The invention will be more readily understood by reference to the accompanying drawings, forming a part of the description, and in which—

Figure 1 is a view, chiefly in vertical or axial section, of a crusher forming a preferred embodiment of the invention. Fig. 2 is a transverse or horizontal sectional view taken on line 2-2 of Fig. 1 and looking downwardly, certain parts above the section-line being indicated in dotted lines, the hydraulic pump being also shown in this view in top plan. Fig. 3 is a side elevation of the parts shown in Fig. 2. Fig. 4 is an elevation or face view of the hydraulic-pump mechanism looking at that side of the latter remote from the crusher.

Referring to the drawings, 1 designates as a whole the main base-frame member, from which is arranged to rise a hollow central column 2, which in turn supports an upper annular supporting-frame 3, these three parts being shown in the present instance as formed integrally, although obviously not so necessarily made.

The tubular column 2 is provided internally with upper and lower spider-frames 4 and 5, respectively, which spiders are bored axially to form suitable bearings 6 and 7 for the upper and lower end portions of the main crusher-head shaft 8. Said shaft is shown as conveniently made of uniform diameter throughout its main length and supported at its lower end by means of a step-bearing

formed by the engagement therewith of an adjusting screw or step 9, threaded through the lower capped end of the lower spider-head. The upper end portion of the main shaft is tapered and carries the conical crusher-head 10, which fits thereupon and is removably connected thereto by means of an axial bolt 11, inserted through the upper end of the crusher-head and threaded into the shaft. The main shaft and crusher-head mounted thereon are free to rotate under the crushing stress, but are not otherwise driven. In order to protect the lower step-bearing from ingress of dirt, the shaft is jacketed by means of a tubular casing 12, interposed between the proximate faces of the spider-hubs, and this casing also constitutes a well which serves to keep both upper and lower bearings submerged in oil.

13 designates as a whole the hopper member, which in the preferred construction shown comprises a main ring or body 14, externally cylindric and internally downwardly conical and of a depth equal to the length of the connections 15, constituting a lining of said ring member and coöperating with the crusher-head in a well-understood manner. The upper side of the main ring 14 carries a plurality of integral radially-projecting arms 16. The arms 16 in turn carry upstanding supports or extensions 17, bolted thereto, as indicated at 18, and upon the supports thus formed and the upper edge of the main ring is supported the outwardly-flaring hopper proper, 19. This hopper may be made of segmental parts, as is common, as indicated by the divisional lines 20. The arms 16, of which there are three, are arranged to extend out through corresponding openings 22, formed in the upstanding rim portion 3' of the frame member 3. The openings 22 are made sufficiently larger than the cross-sectional dimensions of the arms 16 to afford a considerable freedom of movement of the hopper structure, which, as hereinbefore indicated, has imparted thereto a gyratory movement. In order to minimize the friction and to a certain extent guide and confine these arms against lateral movement, I provide pairs of friction-rollers 23, one or more at each side of each arm and journaled upon suitable bearings in suitable recesses 24, formed in the frame member 3', as shown clearly in Fig. 2. The arms 16 referred to 55 constitute the means whereby the hopper structure is supported substantially free from the upper part of the frame structure, and to this end I provide a corresponding series of studs or struts 25, one for each arm 60 16, each strut being interposed between the outer end of the corresponding arm and the base-frame 1. In order to minimize friction, the ends of the struts 25 terminate in balls 26, which fit within corresponding socket-bearings 27 and 28^a, formed in the re-

spective members. The lower sets of ball-and-socket bearings are desirably protected by petticoats 28, secured to and surrounding the lower parts of the struts, as shown clearly in Fig. 1. These ball-and-socket connections also prevent the gyratory outer crusher member from being forced upward in case the crusher becomes choked.

Describing now the means whereby movement is imparted to the hopper structure, 29 75 29', 30 30', and 31 31' designate three pairs of diametrically-opposed hydraulic cylinders, which are formed in the outer ring-frame 3', with their axes radial and preferably perpendicular to the axis of the central crusher-head, these pairs of cylinders being spaced at equal angular distances apart. In the preferred construction shown the cylinders are formed by properly boring the ring-frame member itself, although, of course, independently-formed cylinders might be utilized. The outer ends of the several cylinders are closed by means of suitable caps 32, bolted or otherwise secured to the main frame, and within the inner end of each cylinder is fitted 85 a hydraulic piston 33, provided with suitable circumferential packing-rings 34 and operatively connected with the proximate side of the main ring member 14 of the hopper by means of suitable piston-rods 35. 90 These piston-rods are connected with the pistons and ring member, respectively, by means of suitable ball-and-socket connections, (designated 36 and 37,) which provide for the necessary universal movement, as will hereinafter appear.

The hydraulic pistons 33 are actuated in such manner that as any given piston is moving inwardly against the hopper member its diametrically opposite mate is receding 105 at a corresponding rate and the displacement of the pistons is accomplished progressively around the series, so that the combined action of the several pistons produces a gyratory movement of the hopper. To thus actuate the pistons, each cylinder communicates with a corresponding inlet-pipe, these pipes being shown in the present construction as arranged to communicate with the outer ends of the respective cylinders at the lower sides thereof and being respectively designated 38 38', 39 39', and 40 40'. The several pipes referred to lead to and connect with a hydraulic-pump mechanism, now to be described.

Referring to the Fig. 4, 41 designates a suitable base upon which are mounted two upstanding frames 42 and 43, each carrying a set of pump-cylinders, and a third upright frame, (designated as a whole 44,) provided 115 with a series of journal-bearings, within which are journaled the three shafts 45, 46, and 47, from which motion is communicated to the pump-rods. The frame 44 is shown as comprising a web-like upstanding casting 120 130

48 of angular form in cross-section, its longer web member reaching to and being bolted against one side of the proximate cylinder-frame 42, as indicated at 49, and shafts 47, 5 45, and 46 are held to frame 44, one above the other, by split bearings provided with the usual caps 50, 51, and 52. The central shaft 45 constitutes the main drive-shaft and is provided at its outer end with a driving-pulley 53 and at its opposite end with a spur-gear 54, which also constitutes a pitman-wheel, and to this end is provided with a pitman-wrist 58. Each shaft 46 and 47 is provided with a corresponding spur-gear, as 56 15 and 57, arranged to intermesh with the gear 54, and similarly each provided with a pitman-wrist, as 55 and 59, respectively.

60 60', 61 61', and 62 62' designate the three pairs of pump-cylinders referred to, the 20 cylinders of each pair being arranged in axial alignment with each other in the respective frames 42 and 43 and being located horizontally opposite the corresponding drive-shafts 46, 45, and 47. These pump-cylinders are 25 shown in the present construction as formed by suitably boring or chambering the members 42 and 43, the ends of each cylinder being closed by suitable heads, as 63 and 64. A single plunger-rod is provided for each pair of 30 cylinders, these rods being designated 65, 66, and 67, respectively, and severally arranged to enter the proximate ends of the cylinders through suitable packing-glands 68. With the central part of each plunger is connected 35 a cross-head 69, which has lateral and oppositely-extending arms 70. With the outer ends of each are connected the two arms of a bifurcated connection-rod 71, and the several connecting-rods are at their opposite ends 40 connected with the wrists of the corresponding gear-wheels. In order to strengthen the construction, a slide-bar 72 is arranged to extend between the frame members 42 and 43 a short distance above and parallel with each 45 plunger-rod, and the several cross-heads 69 are provided with extensions 73 at their upper sides, which embrace and slide upon said guide-rods.

To secure a less length of stroke of the pistons 50 65, 66, and 67, I provide in gears 56, 54, and 57 the holes 55^a, 58^a, and 59^a, respectively, nearer the axes of the gears than are the holes in which the wrist-pins are shown on the drawings. The wrist-pins 55, 58, and 59 55 may be removed from the holes in which they are shown inserted and the travel of the connecting-rods lessened by securing them to the gears by inserting the wrist-pins in the holes 55^a, 58^a, and 59^a. It is obvious that 60 the relative positions of the wrist-pins on their several gears must be such as to produce the proper progressive movement of the pistons around the outer crusher member by means of the hydraulic pressure produced by 65 the action of the plungers 65, 66, and 67.

The pipe connections between the several pump-cylinders and the hydraulic cylinders are clearly shown in Figs. 2 and 3 of the drawings, it being noted that each pair of aligned pump-cylinders is connected with a corresponding pair of diametrically-opposed hydraulic cylinders. 70

In order to provide against breakage of parts in case of some obstacle passing into the crusher which cannot be crushed, I provide safety by-pass connections between each pair of aligned pump-cylinders, one set only of these by-pass connections being shown in Fig. 4, but the positions of the others being indicated by the corresponding ports. Describing the same, 74 designates a pipe connected with the cylinder 61 through a port 75 80 and extending thence to and connected with the cylinder 61' to a similar port concealed behind the pipe. In this pipe is interposed a valve-casing 76, within which is arranged to work a relief-valve 77, provided with a stem extending out through a packing-gland 78 in the valve-casing and controlled by a weighted lever 79 in a familiar manner. The arrangement is such that when excess pressure occurs in the cylinder 61' the release thereof will permit the liquid to flow over into the cylinder 61. 80 designates a second by-pass pipe connected at its respective ends with the two cylinders 61 and 61', this device being the complement of the by-pass 74, except that it is arranged so as to relieve the cylinder 61 against excess pressure. It will be understood that a similar 90 pair of by-passes is to be provided for each pair of cylinders. 95

The operation of the apparatus constructed and arranged as described should be entirely obvious from the foregoing description, but may be briefly summarized as follows: Rock discharged into the hopper falls by gravity into the sphere of action of the jaws and is fed downwardly by the continued gyratory movement of the outer crusher member. It is to be noted that the construction dispenses with the usual spider heretofore found necessary, and accordingly there is no liability of the rocks becoming jammed or "bridged," as it is termed, and thus arresting the feed, and this in itself is an important feature of improvement. The connection of the pump mechanism with the hydraulic pistons is such that the inward thrust of each hydraulic piston occurs progressively around the outer crusher member. For example, at the time the piston of cylinder 29 is just approaching its limit of inward movement the piston of the cylinder 29' will be just approaching its limit of outward movement. The piston of the cylinder 30 will be just beginning its inward movement, its opposed mate just beginning its outward movement and the piston of the cylinders 31 and 31' will be in intermediate position. 105 110 115 120 125 130

These relations will change progressively around the crusher-ring, thus bringing about the gyratory movement of the latter. It is to be noted that the three struts which constitute the supports for the gyratory member will severally and simultaneously perform gyratory oscillation at their upper ends, and since they remain at all times at a uniform inclination to the vertical it follows that the bodily-shifting movement of the gyratory member will be confined to a plane which is perpendicular to the central vertical axis of the crusher. The provision of the by-pass connections between the circulating systems of each pair of pump-cylinders insures against breakage of any part of the crusher in case a piece of metal or some substance incapable of being crushed should pass downwardly between the jaws and positively arrest the approaching movement of the gyratory member. In such event the excess of pressure results in opening the safety-valve and permits the fluid to pass over into the opposed pump-cylinder. The provision of means for adjusting the throw of the pump-plunger is obviously a feature of importance, because the length or extent of gyratory movement of the gyratory member of the crusher is directly dependent upon the throw or displacement of the pump-plunger, and accordingly variation in the throw of the latter will result in variation in the movement of the gyratory member. This becomes of importance when it is desired to change the size of the product. For example, in case the product is to be delivered in relatively coarse condition, the power required to reduce the rock to this condition is less, the throw of the gyratory member may be increased, and the rate of delivery will be accelerated. On the contrary, when the rock is to be reduced to a relatively fine condition greater power is required and the shorter and more powerful stroke may be adopted with a corresponding decrease in capacity.

It has been noted in the description of the mechanism that the supporting-frame structure is such that free delivery by gravity is provided down through the central portion of the main frame. This is a feature of much importance, for the reason that it insures perfect delivery and avoids clogging at all times, whereas with the crushers of the prior art, in which the main shaft is gyrated, the eccentric mechanism connected with the lower part of the main shaft has necessitated the use of an inclined diaphragm above this mechanism, with the result that great difficulty has been experienced in the clogging of the machines.

I claim as my invention—

1. In a gyratory crusher, the combination with a central crushing-head, of a surrounding crusher-jaw member supported to move bodily in a plane perpendicular to the axis of

the central crusher-head, and means for gyrating said surrounding crusher-jaw member in its said plane of movement.

2. In a gyratory crusher, the combination with a relatively fixed or bodily-immovable central crusher-head, of a surrounding co-operating crusher-jaw member supported to move bodily in a plane perpendicular to the axis of the central crusher-head, and means for gyrating said surrounding crusher-jaw member in its said plane of movement.

3. In a gyratory crusher, the combination with a non-oscillating circular crusher-head having its axis disposed substantially vertically, of an internally-circular annular crusher member surrounding said crusher-head and supported to move bodily in a plane perpendicular to its own axis of generation, and means for gyrating said annular crusher member in its said plane of movement.

4. In a gyratory crusher, the combination with a suitable supporting-frame, of a centrally-disposed, upwardly-tapering crusher-head, a surrounding upwardly and outwardly flaring crusher member having a completely-open mouth, and means for gyrating said surrounding member.

5. In a gyratory crusher, the combination with a suitable supporting-frame, of a centrally-disposed, upwardly-tapering crusher-head journaled to rotate about its own vertical axis but confined against substantial oscillatory movement, a surrounding internally-circular crusher member having its acting face formed upwardly and outwardly flaring, said member having a completely-open mouth, supports carrying said surrounding crusher member and affording bodily lateral movement of the crusher member in all directions, and means for imparting gyratory movement to said surrounding crusher member.

6. In a gyratory crusher, the combination with a suitable supporting-frame, of a centrally-disposed crusher-head having substantially upright lateral acting surfaces, an open-topped hopper-shaped surrounding crusher member mounted upon supports affording lateral bodily movement thereof in all directions and independent of the movement of the central crusher-head, and means for gyrating said surrounding crusher member relatively to the central cutter-head.

7. In a gyratory crusher, the combination with a suitable supporting-frame, of a centrally-disposed crusher-head and a surrounding crusher member, said crusher-head and crusher member having laterally-opposed upwardly-divergent jaw-surfaces between which the material is reduced, means movably supporting the surrounding crusher member and mechanism for gyrating the latter member bodily, in a plane perpendicular to the axis of the central crusher-head.

8. In a gyratory crusher, the combination

with a centrally-disposed crusher-head, a surrounding crusher member, means supporting said surrounding member to shift bodily laterally relatively to the crusher-head, a plurality of actuating mechanisms arranged at angularly-separated intervals around the exterior of said surrounding crusher member and connecting radially upon the latter, and means for operating said actuating devices to impart gyratory movement to the said crusher member.

9. In a gyratory crusher, the combination with a suitable supporting-frame, of a centrally-disposed upright crusher-head mounted upon said frame, a surrounding hopper-shaped crusher member mounted to move bodily in a plane substantially perpendicular to the vertical axis of the central crusher-head, a plurality of actuating devices disposed at angularly-separated intervals around said outer crusher member and operatively connected with the latter, and means for simultaneously operating said several actuating mechanisms and actuating them so that their several cycles of movements occur in progressive order.

10. In a gyratory crusher, the combination with a suitable supporting-frame, of a crusher-head and a hopper-like annular crusher member, means supporting said hopper member to move bodily and laterally in all directions, a series of thrust-links operatively engaging the exterior of said hopper member and extending substantially radially therefrom, and means for imparting endwise reciprocation to said thrust-links in progressive order around the series.

11. In a gyratory crusher, the combination with a suitable supporting-frame, of a crusher-head and a hopper-like annular crusher member, means supporting said hopper member to move bodily and laterally in all directions, a series of thrust-links operatively engaging the exterior of said hopper member and extending substantially radially therefrom, and means for imparting endwise reciprocation to said thrust-links in progressive order around the series, comprising a hydraulic piston operatively connected with each.

12. In a gyratory crusher, the combination with a suitable supporting-frame, of a central circular crusher-head, a surrounding annular crusher member, means supporting said annular crusher member comprising a series of upright supports each having ball-and-socket connections with the crusher-head and with a suitable fixed support at its respective ends, and means for imparting gyratory movement to said annular crusher member.

13. In a gyratory crusher, the combination of a main frame comprising a base, a central column and a horizontal upper frame member provided with a circumferential up-

standing extension or rim, of a crusher-head supported concentrically within the upstanding or rim portion of the main frame, a hopper-like annular crusher member surrounding said central crusher-head and interposed between the latter and the upstanding rim of the frame, a series of oscillatory struts supporting said hopper-like crusher member and affording movement of the latter in substantially all horizontal directions, and a series of actuating devices mounted upon said rim and arranged to act radially upon said movable crusher member.

14. In a gyratory crusher, the combination of a main frame comprising a base, a fixed horizontally-extending upper frame member provided with a circumferential rim, and one or more supports connecting the upper horizontal frame member with the base-frame, of a crusher-head supported concentrically with said upstanding rim, a hopper-like annular crusher member surrounding said central crusher-head between the latter and the rim, a series of upright struts having their lower ends seated upon the base-frame and their upper ends engaging beneath and supporting the annular crusher member, and a series of actuating devices mounted upon the main frame and adapted to impart gyratory movement to the annular crusher member.

15. In a gyratory crusher, the combination of a main frame provided with a central main shaft and a crusher-head mounted thereon, of a rim forming a part of said main frame and encircling said crusher-head, a hopper-like crusher member interposed between the crusher-head and rim, and a series of hydraulic cylinders formed within said rim with their longitudinal axes radial to the axis of the hopper-like crusher member, pistons in the respective cylinders and piston-rods operatively connecting said pistons with the hopper-like crusher-body, means for supplying hydraulic pressure to said cylinders, and means supporting said hopper-like crusher member to move upon the main frame under the action of said hydraulic pistons.

16. In a gyratory crusher, the combination with a suitable main frame provided with upper and lower shaft-bearings, of a crusher-head shaft journaled in said bearings and carrying at its upper end a crusher-head, a hopper-like crusher member surrounding said crusher-head and movably supported to gyrate upon the main frame relatively to the crusher-head, means for gyrating said hopper-like crusher member, and means for adjusting said central crusher-head vertically and relatively to the hopper-like crusher member.

17. In combination with a gyratory crusher and a plurality of hydraulic cylinders arranged in a circumferential series, a pump mechanism comprising a set of pump-cylinders corresponding in number to, and severally connected with, the hydraulic cylinders.

and intergeared driving connections for actuating the set of pump-cylinder pistons, whereby the pistons of the hydraulic cylinders are actuated in timed relation to each other.

- 5 18. In combination with a gyratory crusher and a plurality of hydraulic cylinders arranged in a circumferential series around the gyratory member of the crusher and each having its piston operatively connected with said gyratory member, a pump mechanism comprising a set of pump-cylinders corresponding in number to, and respectively connected with the hydraulic cylinders, a plunger member working in each pump-cylinder, 15 a connecting-rod for each plunger member and a series of intergeared pitmen-wheels respectively connected with the several plunger members through said connecting-rods, for the purpose set forth.
- 20 19. In combination with a gyratory crusher and a plurality of hydraulic cylinders arranged in a circumferential series around the gyratory member of the crusher, and each having its piston operatively connected with said gyratory member, said hydraulic cylinders being arranged in diametrically opposite pairs, a pump mechanism comprising a set of pump-cylinders corresponding in number to, and respectively connected with, the hydraulic cylinders by individual pipe connections, 25 said pump-cylinders being arranged in coöperative pairs, and each pair of pump-cylinders connected with a corresponding pair of diametrically-opposed hydraulic cylinders, a 30 plunger member working in, and common to, each pair of pump-cylinders, a connecting-rod for each plunger member, and a series of intergeared driving connections for operating the several plunger members in timed relation to each other.
- 35 20. In combination with a gyratory crusher and a plurality of hydraulic cylinders arranged in a circumferential series to act upon the gyratory member of the crusher, and 40 each having its piston operatively connected with said stationary member, said hydraulic

cylinders being arranged in diametrically-opposed pairs, a pump mechanism comprising a set of pump-cylinders corresponding in number to, and respectively connected with, the 50 hydraulic cylinders by individual pipe connections, said pump-cylinders being arranged in coöperative pairs corresponding to the diametrically-opposed pair of hydraulic cylinders, means for moving the plunger of one 55 pump-cylinder inwardly and the plunger of its mate cylinder outwardly together, a by-pass connection between the circulating systems of each pair of pump-cylinders, and a pressure-relief mechanism controlling and 60 normally holding said by-pass closed.

21. In a gyratory crusher, the combination of a main frame having a central passage therethrough from top to bottom for the discharge of the product, a crusher-head shaft 65 carrying at its upper end a crusher-head, skeleton supports or spiders bridging said central passage and supporting said crusher-head shaft centrally therein, an open-topped gyratory annular crusher member surrounding the crusher-head, and means for gyrating said gyratory member.

22. In a gyratory crusher, the combination of a main frame having a central passage therethrough for the discharge of the product, a crusher-head shaft carrying at its upper end a crusher-head, skeleton supports or spiders bridging the central passage and provided with journal-bearings supporting said crusher-head shaft vertically and centrally 70 within said passage, a tubular casing inclosing said shaft completely between the proximate sides of the journal portions of said spiders and a lower end closure inclosing the lower end of the journal-opening of the lower 75 spider, whereby a well is formed for the retention of oil to keep both upper and lower journal-bearings flooded.
